UNITED STATES PATENT OFFICE.

WILLIAM F. STARK, OF NEW YORK, N. Y.

VOLTAIC PLASTER.

SPECIFICATION forming part of Letters Patent No. 293,679, dated February 19, 1884.

Application filed September 20, 1883. (No model.)

To all whom it may concern:

Be it known that I, WILLIAM F. STARK, of the city, county, and State of New York, have invented a new and useful Improvement in 5 Porous or Adhesive Plasters, of which the following is a full and complete description, reference being had to the accompanying drawings.

My invention relates to that class of porous 10 or adhesive plasters to which small pieces of zinc and copper or other suitable metals are attached, whereby upon applying the plaster a galvanic current is excited between those metals by contact with the acid secretions of 15 the body; and it relates more particularly to the mode of placing and attaching such metallic pieces on the plaster.

I am aware of Collins' patent, No. 116,562, July 4, 1871, and aware, also, that it is not 20 new to provide in porous or adhesive plasters metallic strips or wires, to produce a galvanic action.

What I wish to accomplish by my invention 25 is to provide against the skin-poisoning resulting from the contact of copper with the body; and this I accomplish by attaching the zinc to the adhesive side only of the plaster, and the copper to the reverse, connecting, however, the zinc and copper in such a manner, as de- 30 scribed below, that a voltaic current will be excited between the two metals when the plas- ter is applied.

In the accompanying drawings is shown in 35 plan in Figure 1 and in section in Fig. 2 a porous plaster with my galvanic cells attached.

P represents the plaster. The cells are 40 shown in the shape of disks or buttons z and c. The buttons z, which are made of zinc, are shown in the shape of an eyelet-disk, and are riveted through the plaster over the perforated disks or buttons c, of copper, on the other side of the plaster.

Although in the drawings disks are shown, I do not wish to confine myself to the shape of the pieces of metal.

45

It will be readily seen that when the plaster is applied, although the copper pieces do not come in contact with the skin, still they may, through the holes of the eyelets, be acted upon by the acid secretions of the body, and a voltaic current will therefore be excited between the zinc and copper.

The little cells or elements of zinc and copper may be attached to the plaster in any required number, and may be connected together, 55 if desirable, in the usual manner.

Instead of having all the zinc disks on one side of the plaster and all the copper disks on the other, as shown, they may be alternated, so as to bring disks of both metal in contact with 60 the skin, in which case the copper should be silver-plated.

What I claim as my invention, and desire to secure by Letters Patent, is—

1. The combination, with a porous or adhesive plaster, of the eyelets of zinc on the adhesive face thereof, and the perforated pieces of copper on the reverse side, for the purpose of creating a voltaic current and yet avoiding the contact of copper with the skin, substan- 65 tially as described.

2. In a porous or adhesive plaster, the voltaic element composed of an eyelet-piece of zinc attached through the plaster to a corresponding perforated piece of copper on the 70 reverse side of the plaster, for the purpose set forth, and substantially as described.

WILLIAM F. STARK.
